(57) CLAIM

The ornamental design for a service table, as shown and described.

DESCRIPTION

FIG. 1 is a front view of the service table, with a shelf on its right side, showing my new design;
FIG. 2 is a right side view thereof;
FIG. 3 is a top plan view thereof;
FIG. 4 is a perspective view thereof;
FIG. 5 is a front view of the service table, with a shelf on its left side, showing my new design;
FIG. 6 is a right side view thereof;
FIG. 7 is a top plan view thereof;
FIG. 8 is a perspective view thereof;
FIG. 9 is a front view of the service table, with no shelves, showing my new design;
FIG. 10 is a side view thereof;
FIG. 11 is a top plan thereof;
FIG. 12 is a perspective view thereof;
FIG. 13 is a front view of the service table, with shelves on both sides, showing my new design;
FIG. 14 is a side view thereof;
FIG. 15 is a top plan view thereof; and,
FIG. 16 is a perspective view thereof.
